UNITED STATES PATENT OFFICE.

AUGUSTUS L. MEROLLE, OF BROOKLYN, NEW YORK, ASSIGNOR TO EMPIRE METAL CAP CO. INC., OF BROOKLYN, NEW YORK, A CORPORATION OF NEW YORK.

CLOSURE FOR RECEPTACLES.

Application filed October 21, 1920. Serial No. 418,561.

To all whom it may concern:

Be it known that I, AUGUSTUS L. MEROLLE, a citizen of the United States, and a resident of the borough of Brooklyn, in the county 5 of Kings, city and State of New York, have invented certain new and useful Improvements in Closures for Receptacles, of which the following is a specification.

This invention relates to receptacle closures comprising a portion to cover or enclose the open end of a receptacle and having a dependent flange portion to embrace and frictionally engage the side of the receptacle to releasably retain the closure to 10 the open end of the receptacle, and an object of the invention is to provide a closure in which the required strength of frictional engagement against the receptacle may be obtained without the necessity of using especially thick or stiff sheet metal in the manufacture of the closure, that is, one in the manufacture of which sheet metal may be employed which is thinner and cheaper than the sheet metal heretofore employed in the 15 manufacture of this general type of closure but which will nevertheless have its flange portion possessed of the same, or even more gripping power than heretofore, and therefore, to enable this result to be obtained 20 while at the same time enabling a closure of a given size to provide an efficient seal for receptacles considerably varying in size.

A more detailed object is to provide a closure of the type indicated in which the flange thereof is formed at both its upper and lower edge with means serving to reinforce the flange in resisting the expansive movement incident to application of the closure onto a receptacle, and to thereby induce all such expansion to occur in the specifically prepared intermediate portion of the flange.

Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claims.

In the accompanying drawings which are to be taken as a part of this specification, and in which I have shown merely a pre-

ferred form of embodiment of the invention:—

Figure 1 is a perspective view of a receptacle showing my improved closure applied thereto.

Figure 2 is an enlarged sectional detailed view in perspective to show the structure of the closure and the manner of applying the same to the open end of a receptacle, with a sealing material interposed between the closure and the receptacle.

Figure 3 is an enlarged perspective view of the closure looking at the inside thereof with the portion of a sealing material broken away; and

Figure 4 is a view similar to that seen in Figure 2 and illustrating a different form of sealing material.

In carrying out the invention the closure may be made of various sizes to adapt the same for the open end of receptacles of different sizes. In the drawing I have shown a closure embodying my invention applied to the opened end of what is commonly termed as a "jelly glass" in the form of a tumbler.

The closure comprises a disk or cover portion 6 to cover the open end of the receptacle, said disk portion having a dependent annular flange portion 7 which is of concavo convex form in cross section with the convex surface on the interior or curved inwardly from the juncture of the flange with the disk or cover portion to the free edge, as clearly shown in Figure 2, with a continuous wire or bead edge formed by rolling the material at the edge of the flange outwardly, as shown at 8.

The disk or cover portion 6 at the juncture thereof with the flange portion has an annular upwardly extending recessed portion 9 to engage over the upper annular edge of the receptacle, as shown in Figure 2. This annular recess is formed by pressing an annular shoulder or rib into the cover portion at a predetermined point within the juncture of the end and flange portions, as shown at 10, the location of this shoulder 10, depending upon the thickness of the wall of the receptacle at the opening therein. The material of the cover portion within said shoulder 10 is preferably at a somewhat lower plane than the outer portion 9 to engage within the receptacle. The in-

ternal diameter of the flange portion 7 is preferably less than the outer diameter of the open end of the receptacle to which the closure is applied, and in applying the closure to the receptacle pressure is applied to force the same upon the receptacle when the shoulder 10 will engage the inner edge of the wall of the receptacle as shown in Figure 2. The expansion of the flange during its application onto the receptacle will generate a powerful crushing strain of the flange against the outer surface of the receptacle to frictionally although releasable, retain the closure upon the receptacle, and the shoulder 10 will serve to reinforce the receptacle in withstanding the great pressure of the flange.

The flange portion is provided with circumferentially disposed corrugations 11 extending transversely of the concavo convex portion and constructed and arranged so that they will gradually increase in depth from the bead 8 and the juncture of the flange with the cover-portion and be of greatest depth at the middle portion of the flange. These corrugations add great strength to the flange and yet provide for a certain and desirable amount of circumferential expansion of the intermediate portion of the flange. By reason of their vertical disposition and their form and their length they serve to transmit the bursting strains both upwardly and downwardly directly from the point of engagement with the receptacle, that is; upwardly to the juncture of the flange and cover, and downwardly to the wire edge. Both of these portions of the flange being relatively non-yielding they operate to conserve in the intermediate corrugated portion an excessively powerful pressure to supply the needed frictional engagement with the receptacle. It is to be particularly noted in this connection that the wire edge at the bottom of the flange has a cooperative functional value which is of great importance as a reinforcing element since it gives to the lower edge of the flange substantially the same degree of rigidity against expansion and deformation as is given to the upper edge by its integral connection with the cover portion of the closure, and thereby necessitates that substantially all of the expansion taking place in the flange during application onto a receptacle occurs in the intermediate portion of the flange, greatest at the median line and in diminishing degree toward the upper and lower edges.

Where the intermediate portion of the flange is concavo-convex as indicated this expansion of the intermediate portion may result in a slight movement of the upper and lower edges away from each other, which is immaterial, but it is desired that there shall be substantially no expansion

movement of either the upper or lower edge of the flange, and this is an essential feature of the present invention since by means thereof it becomes possible to use in the manufacture of these closures a grade of metal thinner and cheaper than heretofore and yet secure the desired frictional gripping power in the flange.

To prevent material in a receptacle from becoming deteriorated through chemical action of the same upon the inner surface of the closure a sheet of suitable material, such as paraffine paper 12 is interposed, this material being of disk or circular shape and being of a size to engage within the recessed portion 9 whereby as the closure is applied to the receptacle the closure will serve to firmly clamp said sheet in position, and the portion of the sheet engaging between the recessed portion 9 and the end of the receptacle serving as a seal for the closure.

To provide a more positive seal between the closure and receptacle an annular band of sealing material 13 such as rubber or a composition of comminuted cork may be interposed between the edge of the opening of the receptacle and the recessed portion 9 of the closure as clearly shown in Figure 4.

Having thus described my invention I claim:

1. A sheet metal receptacle closure comprising a cover portion and a continuous integral annular flange portion, the cover portion being adapted to rest flat upon the upper annular edge surface of a receptacle and the flange portion being adapted to telescope over the adjacent substantially straight outer surface of the receptacle, the flange portion being resilient and being of a size relative to that of the receptacle requiring it to be expended by forced movement downwardly over the receptacle whereby it will exert throughout its circumference a crushing strain against the receptacle and thereby frictionally retain the closure against displacement, and the cover portion having a downwardly projecting annular shoulder therein arranged to project into the receptacle in engagement with the inner surface of the receptacle to thereby reinforce the receptacle in withstanding the continued pressure of the flange.

2. A sheet metal receptacle closure, comprising a cover portion and a flange portion, the cover portion being adapted to rest flat upon the upper annular edge surface of a receptacle and the flange portion being adapted to telescope over the outer annular surface of the receptacle, the flange portion being resilient and being of a size relative to that of the receptacle requiring it to be expanded by forced telescopic movement downwardly over the receptacle whereby it will exert throughout its circumference a crushing strain against the receptacle and

thereby frictionally retain the closure against displacement, the lower annular edge of the flange portion being turned over upon itself to provide a reinforcing annular wire edge thereon to resist expansion of said lower edge, expansion of the upper edge part of the flange being resisted by its connection with the cover portion, and said flange intermediate its upper and lower edge portions being provided with vertical corrugations which extend from adjacent said upper

edge to adjacent said wire edge and which taper from greater to less depth gradually toward said edges, and serve thereby to transmit bursting strains from the region of greatest depth in opposite directions directly to said edges. ¹⁵

Signed at the city of New York, in the county of New York and State of New York, this 27th day of Sept., 1920.

AUGUSTUS L. MEROLLE.
